UNITED STATES PATENT OFFICE.

WILLIAM P. HECKLER, OF NAPOLEON, OHIO.

FENCEPOST.

1,423,934.

Specification of Letters Patent. Patented July 25, 1922.

Application filed May 14, 1921. Serial No. 469,545.

To all whom it may concern:

Be it known that I, WILLIAM P. HECKLER, a citizen of the United States, residing at Napoleon, in the county of Henry and State 5 of Ohio, have invented certain new and useful Improvements in Fenceposts, of which the following is a specification, reference being had to the accompanying drawings.

This invention relates to fence post structures, and more particularly to corner fence posts.

It is an object of the invention to provide a fence post of this character which is properly held in a vertical position through the 15 medium of a plurality of braces cooperating with each other.

It is another object of the invention to provide a fence post of this character which is insulated from the ground to prevent cor- 20 roding, and wherein the primary supporting brace of the post is connected to the post and also insulated from the ground.

It is also an object of the invention to provide a fence post of this character adapt- 25 ed to be supported by base members formed of imitation stone and wherein the fence post is reinforced and prevented from side movement by braces, one of which is connected to the post and to an imitation stone 30 base member, the remaining braces being connected to the primary brace and to the post in spaced relation to each other.

It is a further object of the invention to provide a post of this character wherein the 35 braces may be connected to the post and arranged in compact form for shipping by disconnecting the braces from the primary brace.

With these and other objects in view the 40 invention consists in the improved construction and arrangement of parts to be herein- after more particularly described, fully claimed and illustrated in the accompanying drawings in which:

Figure 1 is a vertical elevation of a corner fence post, constructed in accordance with an embodiment of the invention,

Figure 2 is an end elevation and sectional view of one of the base members, showing 50 the end of the fence post embedded therein,

Figure 3 is a side elevation and sectional view of another of the base members,

Figure 4 is a top plan view of the base of the main base member, the fence post being 55 shown in section, and

Figure 5 is a side elevation of the braces folded upon the fence post.

Referring to the drawings, 5 designates an imitation stone base member, the sides 6 of said base member tapering from the bottom 60 to the top of the base member, the lower portion of said sides being provided with a flange 7 which serves as an anchor for the base member, the tapering sides being arranged to prevent side movement of the base 65 member within the ground.

When the base member 5 is formed, a corner fence post 8 is positioned centrally of the base member, said fence post being constructed preferably of angle iron, and having bolts 8' or like projections extending through its lower end to assist in anchoring the post within the base member. In view of the fact that the base member surrounds the lower portion of the post, it is impossible 75 for the post at any time to come in contact with the ground. In addition to this the base is considerably larger and heavier than the post, so that danger of the weight of the post overbalancing the base, is eliminated. 80

In order to render the fence post substantial and permit the same to properly sustain the fence wires under tension, there is provided novel bracing means comprising a primary brace member 9, which is made 85 preferably of angle iron or steel, said brace being considerably longer than the post 8. The end 10 of the brace is connected to the upper end portion of the post 8 by means of a bolt or rivet 11. The opposite end 12 90 of the brace 9 is adapted to extend into a base member 13, the end of the flange 14 of the brace member 9, being embedded in the base member, while the extremity of the flange 15 of the brace member 9 engages 95 the upper face of the base member 13. In this way, the end of the flange 14 serves as an anchor for the brace member. The base member 13 is similar in construction to the base member 5, but smaller, and is adapted 100 to be disposed in spaced relation to the base member 5, so that a substantial support is provided for the primary brace 9.

To assist the brace 9 in holding the post 8 in a vertical position, there is provided a 105 plurality of secondary or auxiliary braces 16 and 17, the brace 16 being shorter than the brace 17, and having one of its end portions bolted to the intermediate portion of the fence post 8. The opposite end portion of 110

the brace 16 has the end portion of its flange 18 beveled so as to permit the brace 9 to engage the end portion of the flange 18. In this way, the beveled end portion of the flange 18 serves to properly position the brace 9 with respect to the base 14. The brace 17 is disposed adjacent the ground and has its end 19 bolted or otherwise secured to the fence post 8. The opposite end 20 of the brace 17, similar to the brace 16, has the end portion of its flange 21 beveled so as to permit the end portion of said flange to engage the brace 9.

From the foregoing it will be readily seen that this invention provides a novel form of corner fence post which is properly braced and maintained in position through a novel arrangement of braces and imitation stone base members. The lower end of the fence post and the end of the brace 9 do not come in contact with moisture in the ground as they are disposed centrally of the base member. The flanges on the lower edges of the base members resist any lateral or any like movement of the base members. In addition to this, the intermediate portions of the brace 9 and the fence post 8 are not only reinforced, but the post is provided with additional securing means. It will also be noted that the brace members 16 and 17 may be disconnected from the brace member 9, and folded upon the fence post in parallel relation thereto, together with the brace member 9, so as to render the device compact for shipping. Another feature is that the brace member 9 is connected at three spaced points to the fence post, that is, through the medium of the connection of

the secondary braces and the connection of the brace member 9 to the end of the post, 40 and all of these advantages are possessed by a structure that is simple and compact in form.

What is claimed is:

A fence post of the character described 45 comprising an elongated standard formed substantially L-shaped in cross section, to provide right angular flanges, an elongated primary brace member formed substantially L-shaped in cross section to provide right 50 angular flanges, the end portion of one flange of the primary brace member being connected to the end portion of one flange of the standard, a multiple of secondary brace members, each secondary brace member being formed substantially L-shaped in cross section to provide right angular flanges, one end portion of one flange of each of the secondary braces being pivoted to the standard intermediate its ends, the 60 opposite end of said flange of the secondary braces being beveled and detachably connected to the primary brace, the remaining flange of each of the secondary braces having one end thereof engaged with the remaining flange of the primary brace to prevent relative movement of the secondary braces and primary brace, said secondary braces being detachable from the primary brace to permit movement of the primary 70 brace and secondary braces substantially into parallel relation with the standard.

In testimony whereof I hereunto affix my signature.

WILLIAM P. HECKLER
